UNITED STATES PATENT OFFICE.

VICTOR H. HARBERT, OF SPRINGFIELD, ILLINOIS.

RETAINING-VALVE BRACKET.

Application filed September 16, 1925. Serial No. 56,717.

Retaining valves are applied to cars to make the movement of a train of cars safe, and to conserve the supply of air, and this valve when set and in good working order, 5 does not allow all of the air to escape from the brake cylinder, but retains a certain amount of pressure therein sufficient to hold the brakes in a set position, while the air is being replenished in the train line. When 10 the air pressure in the line is increased or replenished if the retaining valve is in an inoperative condition, the triple valve will automatically assume a released position allowing the train to gain momentum, and 15 run out of control. It is therefore of the utmost importance that the retaining valve be in good working order at all times.

The practice in vogue prior to my invention was to bolt the retaining valve through 20 the car end wall, but this practice has been found objectionable in that the bolt holes in the car wall gradually increase in diameter, due to the service movements of the car, whereby the bolts become loose thus leaving 25 the valve and its pipe free to swing, thereby reducing the efficiency of the valve.

When the retaining valve becomes defective, it is necessary to remove the bolts from 30 the inside of the car whether it be a house car or open car, and if the car happens to be loaded, the load must be removed.

The object of my invention is to provide 35 an anchor for a retaining valve so mounted on the car and of such construction that the retaining valve may be detached from and applied to the anchor without removing the load from the car, thereby reducing the expense of repairs to a minimum, and eliminating the possibility of damage and loss of 40 the contents of the car.

In the drawings:

Figure 1 is a front elevation of my improved bracket, with a retaining valve mounted thereon, in its lowermost position. 45 Figure 2 is a side elevation of the same, with the valve in its uppermost position.

Figure 3 is a front elevation of the bracket detached.

Figure 4 is a sectional view on the line 50 4—4, Figure 3.

Figure 5 is a front elevation of a slightly modified bracket embodying my invention.

Figure 6 is an end elevation of Figure 5.

Figure 7 is a front elevation of a bracket 55 showing another embodiment of my invention.

Figure 8 is a side elevation of Figure 7.

Figure 9 is a top plan view of Figure 7.

Figure 10 is a front elevation of a bracket showing still another modification of my invention. 60

Figure 11 is a side elevation of Figure 10.

Figure 12 is a top plan view of Figure 10.

The reference numeral 13 designates a retaining valve of standard construction provided with side ears 14 and an operating handle 15, the ears 14 being provided with suitable bolt openings. 65

As shown in the drawings, my anchor or bracket is susceptible of many modifications 70 or embodiments without departing from the spirit of my invention.

In the embodiment shown in Figures 1 to 4 the anchor comprises a main body plate 16 having bolt or rivet openings 17 near its upper edge through which bolts or rivets pass to secure the anchor or bracket to the car in a suitable position, at the lower end of the body plate I provide a rebent portion which consists of a forwardly extending 75 spacing member 18 from the forward edge of which a flange 19 extends upwardly and substantially parallel with the body plate 16. This flange 19 is provided with elongated slots 20, spaced to coincide with the bolt openings in the ears 14 of the valve, said slots being open at the upper edge of the flange 19 as shown. 80

If desired, lugs 21 may be formed on the rear face of the flange 19 on each side of the elongated slots 20 to function as rests or supports for the head 23 of the bolts 22 supporting the bolts in an adjusted position before the nuts 24 are tightened. Again, these lugs also function too as abutments to 95 prevent the bolt turning while the nut is being screwed on and off the bolt as will be understood.

In Figures 5 and 6 the construction is substantially the same as shown in Figures 1 to 4 the difference being that the flange 25 extends to the top edge of the body plate 26 as clearly shown in Figure 6, and the body plate is provided with ears 27 extending from its ends, which ears are provided with bolt openings 28 through which bolts pass to secure the anchor to the cars. The flange 25 is provided with elongated slots 29 corresponding with the slots 20 of Figure 3. 100 105 110

In Figures 7 to 9 the construction of the bracket or anchor is like that shown in Fig-

ures 1 to 4, the difference residing in providing the edges or side walls of the elongated slots with projections 30 and depressions 31, the projections 30 on one side of the slot being opposite the depression 31 on the other side of the same slot thereby forming a substantially sinuous slot in the flange 32 of the body plate 33 whereby the bolt will be held in the depressions 31 in preliminary adjusted position.

In Figures 10 to 12 the construction is practically the same as shown in Figures 7 to 9, the only difference being that the projections 34 and the depressions 35 are formed on curves as distinguished from the angular formation shown in Figure 7. In Figures 10 to 12, 36 designates the body plate and 37 the flange.

In use my improved bracket or anchor 20 is bolted or riveted to the wall of the car permanently in the desired positions, the rivets passing through the openings in the body plate.

Now in mounting the valve on my anchor 25 the bolts 22 may be loosely mounted in the holes in the ears 14 of the valve or they may be loosely placed in the elongated slots with the heads of the bolts between the body plate and the flange. In the first application 30 the bolts 22 are positioned near the top of the elongated slots so that if for any reason it is necessary to shorten the air pipe 37 the bolts may be placed in a lower position in the slots as will be understood.

When the valve and bolts 22 are in proper 35 position relative to the anchor the nuts 24 are tightened thereby securing the valve to the anchor firmly.

It will be seen that the valve may be ap-

plied to and detached from the car without entering the car.

What I claim is:

1. A bracket for a retaining valve comprising a flat plate having a return upwardly extending spaced flange at its lower end provided with elongated slots open at the upper edge of the flange, said plate having bolt openings through it.

2. A bracket for retaining valves comprising a flat plate having bolt openings, a spacing member extending forwardly from the lower edge portion of the plate, a flange extending upwardly from said spacing member and substantially parallel with the said plate, elongated slots in said flange open at the top edge of the flange and means on the flange to support a bolt in vertically adjusted position in said slots.

3. A bracket for retaining valves comprising a flat plate having bolt openings, a spacing member extending forwardly from the lower edge portion of the plate, a flange extending upwardly from said spacing member and substantially parallel with the said plate, elongated slots in said flange open at the top edge of the flange and notches formed in the walls of said slots.

4. A bracket for retaining valves comprising a flat plate having bolt openings, a spacing member extending forwardly from the lower edge portion of the plate, a flange extending upwardly from said spacing member and substantially parallel with the said plate, elongated sinuous slots in said flanges open at the top edge of the flange.

In testimony whereof I affix my signature.

VICTOR H. HARBERT.
